United States Patent Office

Des. 212,394
Patented Oct. 8, 1968

212,394

PHOTOGRAPHIC COPYING APPARATUS

Theodore G. Clement, David D. McNair, and Conrad Alt-mann, all of 400 Plymouth Ave. N., Rochester, N.Y.
14608

Filed Oct. 19, 1967, Ser. No. 9,071

Term of patent 14 years

(Cl. D61—1)

FIG. 1

Des. 212,394

FIG. 2

Des. 212,394

We claim:

The ornamental design for a photographic copying apparatus, as shown and described.

UNITED STATES PATENT OFFICE
CERTIFICATE OF CORRECTION

Design No. 212,394

October 8, 1968

Theodore G. Clement et al.

It is certified that error appears in the above identified patent and that said Letters Patent are hereby corrected as shown below:

In the grant, line 2, after "New York," insert -- assignors to Eastman Kodak Company, of Rochester, N. Y., a corporation of New Jersey, --; lines 12 and 13, "Theodore G. Clement, David D. McNair, and Conrad Altmann, their heirs" should read -- Eastman Kodak Company, its successors --. In the heading to the printed specification, lines 4 and 5, "400 Plymouth Ave. N., Rochester, N. Y. 14608" should read -- Rochester, N. Y., assignors to Eastman Kodak Company, Rochester, N. Y., a corporation of New Jersey --.

Signed and sealed this 24th day of February 1970.
